CLAIM

The ornamental design for a loudspeaker as shown and described.

DESCRIPTION

FIG. 1 is a perspective view of a loudspeaker in accordance with our design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines represent portions of the loudspeaker that form no part of the claimed design. The dot-dash boundary line as well as the fogged-out area in FIGS. 1 and 2 that is surrounded by the dot-dash boundary line form no part of the claimed design.
